(57) **CLAIM**

The ornamental design for an antenna structure for radio tracking receiver, as shown and described.

DESCRIPTION

FIG. 1 is a front plan view of an antenna structure for radio tracking receiver of our new design;

FIG. 2 is a rear plan view thereof;

FIG. 3 is an upper perspective view taken from the top and showing the top and front of the design of FIG. 1;

FIG. 4 is a right-hand perspective view and showing the right side and the front of the design of FIG. 1;

FIG. 5 is a left-hand perspective view and showing the left side and the rear of the design, as shown in FIG. 2; and,

FIG. 6 is a lower perspective view taken from the bottom and showing the bottom and front of the design of FIG. 1.
